ASSIGNORS TO UNION SPECIAL MACHINE COMPANY, OF CHICAGO, ILLINOIS, A
CORPORATION OF ILLINOIS

FEEDING MECHANISM FOR TOP ROCK SHAFT MACHINES

Application filed January 26, 1926. Serial No. 83,914.

The invention relates to new and useful improvements in feeding mechanisms for sewing machines, and more particularly to a feeding mechanism used in connection with a cylindrical work supporting arm for feeding the material lengthwise of the arm.

An object of the invention is to provide a feeding mechanism of the above type, wherein the feed bar is so mounted that either end thereof may be raised or lowered during the assembling of the machine for leveling the feed dog or for inclining the same slightly to a horizontal line.

A further object of the invention is to provide a feeding mechanism of the above type which includes a main feed bar carrying the main feed dog, and an auxiliary feed bar carrying the auxiliary feed dog, wherein both feed dogs during the assembling of the parts of the machine may be leveled or inclined as desired.

A still further object of the invention is to provide a feeding mechanism of the above type, wherein the feed bar is supported by swinging link members adjacent the forward and the rear end thereof, and means is provided for maintaining the movement of the feed bar in a vertical plane.

A further object of the invention is to provide a feeding mechanism of the above type wherein the main and the auxiliary feed dogs are given their movements up and down and back and forth, by devices which are actuated by two independent eccentrics.

These and other objects will in part be obvious and will in part be hereinafter more fully disclosed.

In the drawings which show by way of illustration one embodiment of the invention—

Figure 1 is a vertical sectional view through a portion of a sewing machine embodying the improvements;

Fig. 2 is a plan view of the parts shown in Fig. 1, with the cover plate removed so as to show the devices located beneath the same;

Fig. 3 is a longitudinal sectional view through a portion of the upper end of the supporting post and the end of the work supporting arm carried thereby, showing in

particular the manner of mounting the swinging frame by links which carry the inner ends of the feed bars, whereby the same may be raised and lowered;

Fig. 4 is a sectional view on the line 4—4 of Fig. 1;

Fig. 5 is a view showing in section the feed bar removed from the machine, and the upper ends of the supporting devices therefor, and

Fig. 6 is a sectional view on the line 6—6 of Fig. 1.

The invention is directed broadly to a feeding mechanism for a sewing machine having a cylindrical work supporting arm along which the work is fed during the stitching thereof. In the present embodiment of the invention, the work is fed off from the work supporting arm, although the feeding mechanism may be very readily changed so as to feed up the arm instead of off from the arm.

In the present embodiment of the invention, the work supporting arm is carried at the upper end of a supporting post, and the feeding mechanism is actuated by eccentrics located at the lower end of said post through suitable devices extending upwardly in the post and connected to the feed bar operating devices at the upper ends thereof. It will be obvious, of course, that the work supporting arm may be suspended from a depending post instead of being carried at the upper end of a vertical post. In other words, the invention is directed particularly to the packing of the feed bars and the actuating devices therefor, in a cylindrical work supporting arm. The main feed dog is carried by the main feed bar which extends lengthwise of the work supporting arm and is supported on swinging members in the form of vertical links. The forward link is attached at its lower end to a lever which is capable of being oscillated for raising and lowering the feed bar. The fulcrum of this lever is an eccentric member which may be manually adjusted for raising and lowering the front end of the feed bar.

The link at the rear end of the feed bar is mounted on an eccentric bearing which can also be adjusted during the assembling of the parts for raising and lowering the rear end

of the feed bar. This lever for raising and lowering the feed bar is connected to an eccentric strap which cooperates with an eccentric on a shaft extending into the supporting post for the work supporting arm. The feed bar is moved back and forth by a rock lever carried by the work supporting arm adjacent the rear end of the feed bar. This rock lever is connected to an eccentric strap which cooperates with an independent eccentric on said shaft at the lower end of the supporting post for the work supporting arm. The rock lever is connected by a link to the main feed bar so that when said rock lever is oscillated it will move the main feed bar back and forth. The rear end of the feed bar is slabbed so as to provide vertical faces parallel with each other, which extend in between suitable vertical bearing faces formed in a lug on the frame of the machine. These vertical faces on the frame cooperate with the vertical faces on the feed bar in maintaining the up and down and back and forth movements of the feed bar in a vertical plane. In other words, they are for the purpose of preventing the feed bar from tilting, but permit the feed bar to move freely up and down and back and forth. The auxiliary feed bar is mounted on the main feed bar so that it moves up and down therewith. It is, however, moved back and forth independently of the main feed bar by an arm connected by a link to the auxiliary bar and connected by a link to the swinging link support at the rear end of the feed bar. Said swinging link at the rear end of the feed bar is connected to said main feed bar at the upper end thereof, so that the back and forth movements of said feed bar oscillate said swinging link, and the swinging link in turn, through this link connection, oscillates the arm and this imparts back and forth movements to the auxiliary feed bar.

Referring more in detail to the drawings, the improved feeding mechanism includes a cylindrical work supporting arm 1 carried by a vertically extending post 2, which in turn is mounted on a cylindrical arm 3. Located in said cylindrical arm 3 is an actuating shaft 4. Said actuating shaft 4 extends into said post 2 at the lower end thereof. Extending lengthwise of the work supporting arm 1 is a looper supporting shaft 5 on which is mounted a looper 6. At the rear end of this looper supporting shaft there is an arm carrying a ball stud 7. A lever 8 is connected at its upper end to said ball stud 7. This lever is fulcrumed on an arm 9 which is capable of sliding in a sleeve 10 carried by a shaft 11. The shaft 11 is mounted in a bushing 12 in the rear end of the work supporting arm 1. It will be noted that this work supporting arm 1 is separated from the post 2 along the line α — α , and is secured thereto by suitable screws 13. The lower end of the lever 8 is

connected to a crank 14, which crank is rigidly connected to a plate 15 capable of radial adjustment on a disk 16 mounted on the end of the shaft 4. The purpose of this radial adjustment is to vary the stroke of the lever 8. As the shaft rotates, this crank 14 will rotate in a circular path lying in a vertical plane. This causes the upper end of the lever to move to the right and to the left as viewed in Fig. 1, which imparts the endwise movements to the looper shaft and gives a needle avoiding movement to the looper. Said lever 8 is fulcrumed on the arm 9 just below its connection to the ball 7, and this is what causes the upper end of the lever to move back and forth as stated. As the lever 8 moves up and down, due to the rotations of the crank 14, it will oscillate the looper supporting shaft 5 and move the looper into and out of the needle thread loop.

Extending lengthwise of the work supporting arm is a main feed bar 17. Mounted on the left-hand end of this feed bar 17 is the main feed dog 18. The main feed bar 17 is connected to swinging links 19 adjacent the forward end thereof. These links 19 are connected at their upper ends to a pin 20 carried by the feed bar. The lower ends 21 of these links 19 are pivotally connected to a lever 22. The lever 22 is fulcrumed at 23 on a pin 24 which is provided with an eccentric center portion 25. This pin 24 is provided with a slot 26 for a screw driver, whereby it may be turned in its supporting bearing, and the pin is held in adjusted positions by a set screw 27. The lever 22 at its right-hand end as viewed in Fig. 1, is connected at 28 to the upper end of an eccentric strap 29 which cooperates with an eccentric on the actuating shaft 4. As the shaft 4 rotates, it will oscillate this lever 22, and the lever, through the links 19, will raise and lower the forward end of the feed bar. This movement is for the purpose of moving the feed dog into and out of engagement with the material being fed along the work supporting arm.

The inner end of the feed bar 17 is pivoted at 30 to a swinging yoke link 31, and this swinging yoke link 31 is carried by a pin 32 at the lower end thereof. This pin 32 is mounted in an eccentric sleeve 33 which in turn is mounted in a lug 34 formed as a part of the work supporting arm 1. A set screw 35 holds the sleeve 33 in adjusted positions. This sleeve projects slightly beyond the side faces of the lug 34, and therefore, can be reached for adjustment during the assembling of the parts of the machine. It often occurs that the parts to be assembled may be slightly inaccurate or off centers, so that when the feed bar is placed, it is not quite properly positioned for efficient feeding of the material. If it is desired to level the feed dog or tilt it one way or the other relative to a horizontal line, this can be done by loosen-

ing the set screw 35 and adjusting this eccentric sleeve 33. The adjusting of this eccentric sleeve, together with the adjustment of the eccentric sleeve on which the lever 22 is 5 fulcrumed, provides means whereby either end of the feed bar can be raised or lowered for the leveling or positioning of the feed dog carried thereby. By this means just described, the longitudinal axis of the path of 10 travel of the feed dog may be adjusted bodily vertically or the angle thereof changed to various set positions, and this can be accomplished without varying the length of the stroke of the feed dog or the rising and falling movements thereof, or in any way changing the character of the path of movement 15 of the feed dog.

The main feed bar 17 is provided at its rear end with a projecting portion 36 which 20 is slabbed so as to provide vertical faces which are adapted to fit between the vertical faces of the parallel members 37 carried by the lugs 34. The projecting portion 36 of the feed bar is free to move up and down 25 and back and forth between these members 37. The purpose of the members 37 is to prevent any lateral tilting of the feed bar as it moves back and forth with the swinging link members 19 and 31. Thus it is that the portion 36 serves to guide the feed bar in its 30 movements, and not only prevents the tilting of the same, but any lateral shifting of the feed bar on its supporting links.

This main feed bar 17 is moved back and 35 forth by a link 38 which is pivoted at 39 to the main feed bar. The rear end of this link 38 is pivoted at 40 to a rock lever 41 which is mounted on a pivot stud 42 threaded into the lug 34. The rock lever 41 has a 40 rearwardly projecting arm 43 which is connected to an eccentric strap 44, and this eccentric strap 44 in turn cooperates with an eccentric on the actuating shaft 4. It is noted that the stud 45 carried by the arm 43 45 and to which the eccentric strap 44 is connected, has a cone face, with the base of the cone at the outer end of the stud. Said cone stud is provided with a screw slot 46. The stud has a threaded portion 47 which is 50 threaded into the arm 43. By turning the cone stud, it may be threaded into or out of the arm 43, so as to adjust the same, and said cone stud is held in adjusted positions by means of a lock nut 48. There is a similar 55 cone stud connection between the lever 22 and the eccentric strap 29. As the actuating shaft 4 rotates, the eccentric strap 44 will rock the lever 41, and the lever 41 will in turn move the link 38 back and forth on the 60 work supporting arm, and thus move the main feed bar back and forth.

The auxiliary feed dog 49 is carried by an auxiliary feed bar 50. The main feed bar 17 is provided with a longitudinal slot or 65 recess 51 in which the auxiliary feed bar 50

is located. The auxiliary feed bar is free to move endwise in this slot or recess 51, and is moved by a link 52 pivotally connected at 53 to the auxiliary feed bar. This link, at its other end, is pivoted at 54 to an arm 55, which 70 arm is provided with spaced lugs 56, 56 at its lower end (see Fig. 6), mounted on the fulcrum pin 24 for the lever 22. The lever 22 extends between these lugs 56, 56. The parts of the pin 24 on which said lugs are 75 mounted are concentric with the center of said pin, so that when said pin is rotated for the purpose of raising and lowering the fulcrum point of the lever 22, such adjustment does not in any way raise or lower the arm 55. 80 The arm 55 in turn is connected to a link 57 at 58, and the link 57 is connected to a stud 59 mounted in an arc-shaped slot 60 formed in the swinging yoke link 31. This slot 60 is curved about the point 58 as a center. Said 85 stud 59 is moved along the slot by means of a lever 61 connected by a short link 62 to the link 57. This lever 61 is rigidly connected to a shaft 63 and on said shaft is a rigidly 90 connected arm 64. Said arm 64 is in turn connected to a crank pin 65 mounted on a disk 66 rigid with a short shaft 67. The arm 64 is provided with a slot 64^a extending lengthwise thereof which receives the pin 65, and this establishes a connection between the 95 crank pin and the arm. The shaft 67 likewise carries an arm 68 which extends beneath a fixed segment plate 69. A finger piece 70 is secured to the arm 68 and is capable of being 100 moved along said segment plate 69, and held in adjusted positions along the same in the usual manner. When this finger piece 70 is shifted along the segment plate, it will rock the disk 66, which, through the crank pin 65, will raise or lower the right-hand end of the 105 arm 64. This will in turn raise or lower the lever 61 and shift the stud 59 in the slot. The purpose of this adjustment of the stud 59 is to vary the stroke of the auxiliary feed bar. The swinging yoke link 31 is connected by 110 means of the pivot bolt 30 to the rear end of the main feed bar 22 so that as the main feed bar moves back and forth, it will swing this yoke link 31, and the yoke link 31, through its connection with the auxiliary feed bar, will move said auxiliary feed bar back and forth. By shifting the stud 59 the extent of movement of the auxiliary feed bar may be made greater than the main feed 115 bar, or if desired, may be made less than the movement of the main feed bar. This auxiliary feed bar is raised and lowered as above noted with the main feed bar. Both of the feed bars, therefore, derive their back and forth and up and down movements from the 120 two eccentrics which operate upon the eccentric straps 29 and 44. The eccentric strap 29 through the lever 22 moves the main feed bar up and down, and as the auxiliary feed bar moves up and down therewith, both feed bars 125 130

are raised and lowered by this eccentric strap 29. Both the main and the auxiliary feed dogs are, therefore, raised into engagement with the material, and lowered out of engagement with the material, through the aid of this eccentric strap 29. The main feed bar is moved back and forth by the eccentric strap 44 operating through the rock lever 41, and the link 38. The inner end of this link 38 is connected to a stud which can be adjusted in a slot formed in the arm of the rock lever 41, and thus the stroke imparted to the main feed bar varied. The main feed bar as it moves back and forth, oscillates the yoke link 31 through the pivot connection 30 therewith, and the yoke link imparts the back and forth movements to the auxiliary feed bar, so that both feed bars are reciprocated by means of the eccentric strap 44, and the devices which connect this eccentric strap 44 to the auxiliary feed bar are capable of adjustments so that the movement of a different length may be given the auxiliary feed bar from that given the main feed bar. The movement of the main feed bar can also be adjusted.

The main feed dog 18 is secured to the main feed bar by means of a screw 72. The auxiliary feed dog is secured to the auxiliary feed bar by a screw 73. The auxiliary feed dog slides back and forth on the shank of the main feed dog. The auxiliary feed bar 50 is held in the recess or slot 51 by a plate 74 which is secured to the main feed bar by a screw 75. This plate is located in a recess formed in the side face of the auxiliary feed dog and overlies the bottom wall of the recess. The recess is long enough so that the auxiliary bar is free to move endwise, but cannot move vertically relative to the main feed bar.

From the above it will be noted that a feeding mechanism for a cylindrical work supporting arm has been provided, wherein the parts are so constructed and arranged that the feed dogs are positively moved back and forth and raised and lowered, and through the aid of comparatively few parts. Furthermore, the feeding mechanism has been provided, wherein the feed bars may be leveled or inclined during the assembling of the parts in order to insure the proper setting of the feed dogs. While the feeding mechanism is shown and described as feeding the material off the work supporting arm, it will be understood, of course, that it may be readily used for feeding the material on to the arm, if so desired. Of course, in order to bring this about, the devices for moving the feed bars back and forth would have to be changed and timed to accomplish the movements of the feed dogs in proper timing with the movements of the stitching mechanism. While the cylindrical work supporting arm has been shown as mounted on the

upper end of a post with the shaft extending into the lower end thereof, it will also be readily understood that the work supporting arm may be suspended from a depending member, wherein the actuating shaft is above 70 the feed bars.

It is obvious that minor changes in the details of construction and the arrangement of the parts may be made without departing from the spirit of the invention as set forth 75 in the appended claims.

Having thus described the invention, what we claim as new and desire to secure by Letters Patent, is—

1. A feeding mechanism for sewing machines including a supporting member, a feed bar mounted in said supporting member, a feed dog carried thereby, swinging members located adjacent the opposite ends of said feed bar and pivotally connected thereto for 80 supporting the same, a lever extending lengthwise of the feed bar and pivotally connected with the swinging member at the forward end of the feed bar, means for oscillating said lever for raising and lowering the 85 forward end of the feed bar, means independent of said swinging members connected to said feed bar for moving the same back and forth on said swinging members and means for preventing lateral tilting of said feed bar 90 as it moves back and forth with said swinging members.

2. A feeding mechanism for sewing machines including a supporting member, a feed bar mounted in said supporting member, a feed dog carried thereby, swinging members located adjacent the opposite ends of said feed bar and pivotally connected thereto for supporting the same, a lever extending lengthwise of the feed bar and pivotally connected with the swinging member at the forward end of the feed bar, means for oscillating said lever for raising and lowering the forward end of the feed bar, means connected to said feed bar for moving the same back and forth on said swinging members, an eccentric member for supporting said swinging member at the rear end of said feed bar, said eccentric member being mounted in said supporting member for the feed bar, and means for holding said eccentric member in various adjusted positions, said eccentric member being capable of adjustment for raising and lowering the rear end of the feed bar.

3. A feeding mechanism for sewing machines including a supporting member, a feed bar mounted in said supporting member, a feed dog carried thereby, swinging members located adjacent the opposite ends of said feed bar and pivotally connected thereto for supporting the same, a lever extending lengthwise of the feed bar and pivotally connected with the swinging member at the forward end of the feed bar, means for oscillating said lever for raising and lowering the 130

forward end of the feed bar, means connected to said feed bar for moving the same back and forth on said swinging members, an eccentric member for supporting said swinging member at the rear end of said feed bar, said eccentric member being mounted in said supporting member for the feed bar, means for holding said eccentric member in various adjusted positions, said eccentric member being capable of adjustment for raising and lowering the rear end of the feed bar, an eccentric member on which said lever is mounted, and means whereby said eccentric member can be adjusted and held in adjusted positions for raising and lowering the front end of the feed bar.

4. A feeding mechanism for sewing machines including a work supporting cylinder, a feed bar extending longitudinally of said cylinder, a feed dog carried thereby, swinging links located substantially at opposite ends of the feed bar and pivotally connected thereto for supporting the same, a lever extending longitudinally of said cylinder and pivotally supporting the link at the forward end of the feed bar, means for oscillating said lever for raising and lowering the feed dog, and means independent of the swinging links connected with said feed bar intermediate the ends thereof for moving said feed bar back and forth and means engaging the feed bar independently of the links for guiding the feed bar in its up and down and endwise movements, so as to prevent tilting or lateral shifting of the feed bar.

5. A feeding mechanism for sewing machines including a work supporting cylinder, a feed bar extending longitudinally of said cylinder, a feed dog carried thereby, swinging links located substantially at opposite ends of the feed bar and pivotally connected thereto for supporting the same, a lever extending longitudinally of said cylinder and pivotally supporting the link at the forward end of the feed bar, means for oscillating said lever for raising and lowering the feed dog, means connected with said feed bar intermediate the ends thereof for moving said feed bar back and forth, an eccentric member on which the swinging link at the rear end of the feed bar is mounted, and means whereby said eccentric member can be adjusted and held in adjusted positions for raising and lowering said swinging link.

6. A feeding mechanism for sewing machines including a work supporting cylinder, a feed bar extending longitudinally of said cylinder, a feed dog carried thereby, swinging links located substantially at opposite ends of the feed bar and pivotally connected thereto for supporting the same, a lever extending longitudinally of said cylinder and pivotally supporting the link at the forward end of the feed bar, means for oscillating said lever for raising and lowering the feed dog, means

connected with said feed bar intermediate the ends thereof for moving said feed bar back and forth, an eccentric member on which the swinging link at the rear end of the feed bar is mounted, means whereby said eccentric member can be adjusted and held in adjusted positions for raising and lowering said swinging link, an eccentric member on which said lever is mounted, and means for adjusting said eccentric member and holding the same in adjusted positions for raising and lowering the forward end of said feed bar.

7. A feeding mechanism for sewing machines including a work supporting cylinder, a feed bar extending longitudinally of said cylinder, a feed dog carried thereby, swinging links located substantially at opposite ends of the feed bar and pivotally connected thereto for supporting the same, a lever extending longitudinally of said cylinder and pivotally supporting the link at the forward end of the feed bar, means for oscillating said lever for raising and lowering the feed dog, a rock lever independent of said swinging links located adjacent the rear end of said feed bar, a link having an adjustable connection with said rock lever and connected with the feed bar intermediate the ends thereof, and means for oscillating said rock lever for moving the feed dog back and forth.

8. A feeding mechanism for sewing machines including a work supporting cylinder, a feed bar extending longitudinally of said cylinder, a feed dog carried thereby, swinging links pivoted to said feed bar adjacent the opposite ends thereof for supporting the same, a lever extending longitudinally of said cylinder and pivotally supporting the link at the forward end of the feed bar, an actuating shaft, an eccentric thereon, an eccentric strap cooperating with said eccentric and directly connected to said lever for oscillating the same to raise and lower the feed dog, a rock lever independent of said swinging links adjacent the rear end of said feed bar, a link connecting said rock lever to the feed bar intermediate the ends thereof, a second eccentric on said actuating shaft, and an eccentric strap cooperating therewith and directly connected to said rock lever for moving said feed bar back and forth.

9. A feeding mechanism for sewing machines including a work supporting cylinder, a feed bar extending longitudinally of said cylinder, a feed dog carried thereby, swinging links pivoted to said feed bar adjacent the opposite ends thereof for supporting the same, a lever extending longitudinally of said cylinder and pivotally supporting the link at the forward end of the feed bar, an actuating shaft, an eccentric thereon, an eccentric strap cooperating with said eccentric and directly connected to said lever for oscillating the same to raise and lower the feed dog, a rock lever adjacent the rear end of said feed

bar, a link connecting said rock lever to the feed bar intermediate the ends thereof, a second eccentric on said actuating shaft, an eccentric strap cooperating therewith and directly connected to said rock lever for moving said feed bar back and forth, an eccentric member for supporting the link at the rear end of the feed bar, and means for adjusting said eccentric member and holding the same in adjusted positions during the assembling of the parts for leveling the feed dog.

10. A feeding mechanism for sewing machines including a work supporting arm, a feed bar extending longitudinally thereof, a feed dog carried by said feed bar, swinging links located substantially at opposite ends of the feed bar and pivotally connected thereto for supporting the feed bar, means for raising and lowering the link at the forward end of the feed bar for raising and lowering the feed dog, means independent of the swinging links and connected with the feed bar intermediate the ends thereof for moving said feed bar longitudinally, said feed bar at the rear end thereof having a projecting portion provided with vertical faces, said work supporting arm having spaced members between which said projecting portion of the feed bar moves, said members having free contact with the vertical faces on the feed bar for preventing any lateral tilting of the feed dog as the feed bar moves back and forth on said swinging links.

11. A feeding mechanism for sewing machines including a work supporting arm, a main feed bar extending longitudinally of said work supporting arm, a feed dog carried thereby, said feed bar having a recess in the upper face thereof, an auxiliary feed bar located in said recess, means for holding said auxiliary bar in said recess and permitting the endwise movement of the auxiliary bar relative to the main bar, an auxiliary feed dog carried by said auxiliary feed bar, swinging links located substantially at opposite ends of said main feed bar and pivotally connected thereto for supporting the same, a lever extending longitudinally of said arm on which the forward link is pivoted, means for oscillating said lever to raise and lower the main feed bar, means connected with the main feed bar intermediate its length for moving said feed bar back and forth, a pivoted vertical arm located intermediate the ends of the main feed bar, a link connecting said arm to the auxiliary feed bar, a link connecting said arm to the swinging link at the rear end of the feed bar whereby the oscillations of said last-named swinging link impart endwise movement to the auxiliary feed bar, part endwise movement to the auxiliary feed bar.

12. A feeding mechanism for sewing machines including a work supporting arm, a main feed bar extending longitudinally of said work supporting arm, a feed dog car-

ried thereby, said feed bar having a recess in the upper face thereof, an auxiliary feed bar located in said recess, means for holding said auxiliary bar in said recess and permitting the endwise movement of the auxiliary bar relative to the main bar, an auxiliary feed dog carried by said auxiliary feed bar, swinging links located substantially at opposite ends of said main feed bar and pivotally connected thereto for supporting the same, a lever extending longitudinally of said arm on which the forward link is pivoted, means for oscillating said lever to raise and lower the main feed bar, means connected with the main feed bar intermediate its length for moving said feed bar back and forth, a pivoted vertical arm located intermediate the ends of the main feed bar, a link connecting said arm to the auxiliary feed bar, a link connecting said arm to the swinging link at the rear end of the feed bar whereby the oscillations of said last-named swinging link impart endwise movement to the auxiliary feed bar, said swinging link at the rear end of the feed bar having an arc-shaped slot carrying a stud to which the link which imparts movements to the auxiliary feed bar is connected, and manual means for shifting the position of the stud in said arc-shaped slot for varying the throw of the auxiliary feed bar.

13. In a feeding mechanism for sewing machines, the combination of a feed bar, a feed dog mounted on said feed bar, means for imparting feeding movements to said feed bar, and means adjacent each end of said feed bar for supporting the same, each of said supporting means including devices capable of being adjusted whereby the longitudinal axis of the path of travel of the feed dog may be adjusted bodily vertically or the angle thereof changed to various set positions without changing the character of the path of movement of the feed dog.

14. In a feeding mechanism for sewing machines, the combination of a feed bar, a feed dog mounted on said feed bar, means for imparting feeding movements to said feed bar, and pivotally mounted means adjacent each end of said feed bar for supporting the same, each of said supporting means including devices capable of being adjusted whereby the longitudinal axis of the path of travel of the feed dog may be adjusted bodily vertically or the angle thereof changed to various set positions without changing the character of the path of movement of the feed dog.

15. In a feeding mechanism for sewing machines, the combination of a feed bar, a feed dog mounted on said feed bar, means for imparting feeding movements to said feed bar, pivotally mounted supporting devices at each end of said feed bar for supporting the same, each device including an

eccentric member capable of adjustment to various set positions whereby the longitudinal axis of the path of travel of the feed dog may be bodily vertically shifted or the angle thereof changed to various set positions without changing the character of the path of movement of the feed dog.

- 5 16. A feeding mechanism for sewing machines including in combination, a feed bar, 10 a feed dog mounted on said feed bar, devices for imparting rising and falling movements to said feed bar, devices for imparting back and forth movements to said feed bar, pivotally mounted means for supporting said feed bar adjacent the front and rear ends thereof, each of said pivotal mountings including an eccentric member adjustable to various set positions whereby the longitudinal axis of the path of travel of 15 20 the feed dog may be bodily adjusted vertically or the angle of said longitudinal axis changed without changing the character of the path of movement of the feed dog.

- 25 17. In a feeding mechanism for sewing machines, the combination of a feed bar, a feed dog mounted on said feed bar, means for imparting feeding movements to said feed bar and means for supporting said feed bar adjacent the front and rear ends thereof, each of said supporting means including devices capable of being adjusted whereby said feed bar may be adjusted vertically at either end for altering the position of the longitudinal axis of the path of travel 30 35 of the feed bar without changing the character of the path of movement of the feed dog.

- 40 18. A feeding mechanism for sewing machines including in combination a feed bar, a feed dog mounted on said bar, means for imparting feeding movements to said feed bar, pivotally mounted supporting means for said feed bar located adjacent the front and rear ends thereof, each of said supporting 45 means including devices capable of being adjusted whereby the feed bar may be adjusted vertically at either end thereof, each of said devices including an eccentric member adjustable to various set positions without 50 changing the character of the path of movement of the feed dog.

In testimony whereof, we affix our signatures.

JAMES R. MOFFATT.
RALPH S. KELSO.
